UNITED STATES PATENT OFFICE.

ALEXANDER T. KASLEY, OF PHILADELPHIA, PENNSYLVANIA, ASSIGNOR TO WESTINGHOUSE ELECTRIC & MANUFACTURING CO., A CORPORATION OF PENNSYLVANIA.

MOUNTING FOR TURBINE-BUCKETS.

1,345,678.

Specification of Letters Patent. Patented July 6, 1920.

Application filed June 25, 1918. Serial No. 241,882.

To all whom it may concern:

Be it known that I, ALEXANDER T. KASLEY, a citizen of the United States, and a resident of Philadelphia, in the county of Philadelphia and State of Pennsylvania, have made a new and useful Invention in Mounting for Turbine-Buckets, of which the following is a specification.

This invention relates to turbine buckets and particularly to that class of turbine buckets used in steam turbines wherein a series of impulse or reaction buckets are mounted in a row upon a turbine rotor.

This invention has for its principal objects the production of a rotor and bucket construction for turbines wherein the buckets may be readily applied and removed from the motor; the production of an improved structure for attaching the bucket shanks to a rotor rim so that they can be applied to the rim substantially from the side thereof; and the production of a simple, inexpensive and efficient mounting for the buckets and such other objects as may hereinafter appear. Certain embodiments of the invention are illustrated in the accompanying drawings, wherein—

Figure 1 is a side elevation of the side of the turbine rotor showing the bucket mounting.

Fig. 2 is an enlarged section on the line II—II of Fig. 1 and

Fig. 3 is a similar section of a modified form of rotor and buckets.

Referring to the drawings: 4 is a turbine rotor having a rim 5 carrying a pair of peripheral flanges 6 and 7 spaced apart so as to provide a bucket groove 8 between them. The bucket retaining flange 6 is of greater height from the bottom of the groove 8 to the periphery of the flange than the depth of the flange 7, and is provided with an annular overhanging projection 9 which serves to prevent displacement of the radially disposed buckets 10.

The bucket 10 is provided with a shank 11 having a projection 12 at its lower end which is adapted to fit under the projecting ridge 9 so that it will be held firmly against the action of centrifugal force tending to throw the bucket from the rotor. The underside of the ridge or projection 9 is preferably disposed at right angles to the

inner face of the flange 6, which construction provides a secure locking connection between the bucket shank 11 and the rotor.

55

Referring to Fig. 2, it will be seen that the enlarged end of the shank 11 is of less width than the narrowest opening in the groove 8 and that the bucket shank 11 may be inserted in the groove laterally toward the flange 6. Under some conditions of assembly it is preferable to insert the blade from the side of the rotor instead of from the periphery and one of the objects of this invention is to provide a simple rim construction for the rotor having the flange 7 integral with the rotor 4. It will be obvious that if the flange 7 were extended above the bottom of the groove 8 the same distance as the flange 6, it would not be possible to insert the bucket shank 11 from the side of the rotor, and in this case the bucket could not be inserted from the periphery because the width of the bucket groove 8 would not permit the enlarged portion of the shank to pass into the groove. The bottom of the groove 8 is wider than the greatest width of the bucket shank 11, which construction leaves a space between the flange 7 and the lower portion of the bucket shank into which a pair of wedge members 13 are inserted for the purpose of pressing the lower end of the shank 11 toward the flange 6. The pressure of the wedges opposes any tendency that the bucket might have to rotate about the projection 9 of the flange 6 as a pivot. It will be seen that the above construction provides a very simple and efficient mounting for a turbine bucket. It will also be observed that the bucket shanks 11 are held against radial displacement, simply by a projection 12 provided on one side of the bucket shank so that less machining is required in the manufacturing of the buckets.

95

The flange 7 is undercut and the outer face of the wedge 13 is made to conform to the contour of the undercut side of the flange 7, so that when the wedges are inserted and are driven into holding position they will not be displaced by centrifugal force. In the assembly of the wedges it will be obvious that the outer wedge adjacent the flange 7 will be inserted first, after which the inner wedge can be driven into place. This form of mounting for the buck-

100

105

ets necessitates a minimum of machining operations and consequently the construction may be produced at a comparatively small cost.

5 Referring to Fig. 3, wherein a modified form of rotor and bucket mounting is illustrated, 4' is a rotor provided with a rim 5', having peripheral flanges 6' and 7' integral therewith and spaced apart so as to provide 10 a bucket groove 8' between them. The flange 6' is provided with an annular projection 9' for retaining the bucket 10'.

The bucket 10' is provided with a shank 11' having a projection 12' at its lower end, 15 which is adapted to fit beneath the annular projection 9' carried by the flange 6'. This portion of the construction is practically the same as the construction illustrated in Figs. 1 and 2. The difference of the construction 20 however resides in a different form of flange 7' and a slight difference in the contour of the free side of the shank 11'.

In this construction, the flange 7' does not project above the bottom of the groove 8' 25 as far as the groove 7 of the construction illustrated in Fig. 2. In this case, the wedge member 13' is mounted in a groove 14 cut in the outer bottom portion of the groove 8. The lower corner of the shank 11' is cut 30 away at 15, as shown in Fig. 3, and the pressure of the wedges is consequently exerted in a direction diagonally upward toward the annular projection 9', thereby exerting a force opposing any force tending to rotate 35 the bucket about the projection 9' as a pivot. This construction can be made as cheaply as the construction previously described and is just as efficient. This construction, however, has the advantage that the buckets 40 10' may be placed in position by a lateral movement thereof with practically no endwise displacement.

While I have described and illustrated but two embodiments of my invention, it will 45 be apparent to those skilled in the art that various modifications, changes, additions, and omissions may be made in the apparatus described and illustrated without departing from the spirit and scope of the invention 50 as set forth by the appended claims.

What I claim is:

1. A turbine mechanism comprising a rotor having a peripheral bucket retaining flange having an overhanging portion, a radially disposed bucket having a shank with a projection adapted to fit under the overhanging portion whereby radial displacement of the shank is prevented, a flange of less diameter for preventing lateral displacement of the shank and a binding member disposed between the second flange and the shank adapted to hold the shank in engagement with the first flange.

2. A turbine mechanism comprising a rotor having a peripheral bucket retaining

flange having an overhanging portion, a radially disposed bucket having a shank with a projection adapted to fit under the overhanging portion whereby radial displacement of the shank is prevented, a flange 70 having a periphery of less diameter than the periphery of the first flange, for preventing lateral displacement of the shank, and a binding member disposed between the second flange and the shank adapted to hold 75 the shank in engagement with the first flange.

3. A turbine mechanism comprising in combination a rotor having a pair of peripheral flanges of different diameters 80 spaced apart to form a bucket groove, the flange of greater diameter being provided with an overhanging portion near the periphery, a radially disposed bucket having a shank provided with a projection adapted 85 to fit under the overhanging portion whereby radial displacement of the bucket is prevented, and a binding member disposed between the free side of the shank and the other flange at a point below the overhanging 90 member for preventing lateral displacement of the bucket shank.

4. A turbine mechanism comprising in combination a rotor having a pair of peripheral flanges of different diameters 95 spaced apart to form a bucket groove, the flange of greater diameter being provided with an overhanging portion, a radially disposed bucket having a shank provided with a projection adapted to fit under the overhanging portion whereby radial displacement of the bucket is prevented, and a wedge member disposed between the other flange 100 and the lower portion of the shank at a point below the overhanging portion, 105 whereby the shank is securely clamped between the said flange and the overhanging portion.

5. The combination with a turbine member having an undercut groove, of a bucket 110 having a shank of less width than the groove and having a projection on one side of the shank conforming substantially to the form of the undercut portion of the groove and a binding member disposed between the other 115 side of the groove and the bucket shank adapted to engage the shank adjacent the lower end thereof, one side of the groove being lower than the other whereby the buckets may be axially inserted in assembling the buckets on the member.

6. In a mounting for turbine blades, a turbine member, an overhanging flange formed on said member, a bucket having a projection formed to fit under the overhanging portion of the flange whereby substantially all of the centrifugal stresses imposed on the bucket are absorbed by the single flange, a groove formed in the face of the turbine member adjacent the free side of the 130

bucket, and means inserted in said groove for preventing lateral displacement of the bucket.

7. In a mounting for turbine blades, a turbine member, an overhanging flange formed on said member, a bucket having a projection formed to fit under the overhanging portion of the flange whereby substantially all of the centrifugal stresses imposed on the bucket are absorbed by the single flange, a groove formed in the face of the turbine member adjacent the free side of the bucket, and means inserted between said groove and the bucket for preventing lateral displacement of the bucket.

8. Mounting means for turbine blades, comprising an overhanging flange on the

member on which the blades are to be mounted, a blade having a shank shaped on one side to fit the overhanging flange, a groove formed in the member adjacent the free side of the blade shank, and a diagonal key inserted in said groove and bearing against the shank for preventing lateral displacement thereof, due to the eccentric mounting of the shank.

In testimony whereof I have hereunto subscribed my name this 20th day of June, 1918.

ALEXANDER T. KASLEY.
